UNITED STATES PATENT OFFICE.

FRANK D. HOWE, OF CUYAHOGA FALLS, OHIO, ASSIGNOR, BY MESNE ASSIGNMENTS,
TO INTERNATIONAL HARVESTER COMPANY, A CORPORATION OF NEW JERSEY.

MAGNETO DRIVE.

1,413,479.

Specification of Letters Patent. Patented Apr. 18, 1922.

Application filed May 16, 1918. Serial No. 234,970.

To all whom it may concern:

Be it known that I, FRANK D. HOWE, a citizen of the United States, residing at Cuyahoga Falls, in the county of Summit 5 and State of Ohio, have invented certain new and useful Improvements in Magneto Drives, of which the following is a full, clear, and exact specification.

This invention relates to couplings for 10 driving shafts and is particularly adapted for use on magnetos.

The object of the invention is to provide a driving means for magneto shafts whereby the shaft of the magneto may be retarded 15 or completely stopped for an instant and then be driven forward with a sudden impulse. This is particularly useful in starting an internal combustion engine running on a magneto where the low speed of the armature shaft of the magneto when directly 20 driven will not give a sufficiently hot spark to ignite the charge in the cylinder.

Another object is to provide means for holding the retarding device out of operation 25 so that the armature is continuously driven by the driving shaft.

Another object is to provide a coupling means which does not require that the armature shaft of the magneto and the driving 30 shaft be in perfect adjustment, but which will automatically adjust itself for small variations therein.

Another object is to provide a device having the foregoing advantages and which is 35 at the same time of neat appearance and which can be economically manufactured.

These and other objects are accomplished 40 by my invention which comprises a driving shaft and a driven shaft substantially in alignment, yieldable means connecting the two shafts and a spring pressed roller adapted to retard the driven shaft.

Referring now to the drawing in which like reference numerals refer to like parts 45 throughout,—

Figure 1 is a side elevation of my invention applied to a magneto;

Fig. 2 is an end elevation of the same; and Fig. 3 is the same as Fig. 2 but showing 50 a modification.

My invention comprises a magneto 10 having an armature shaft 11, which I shall also call a driven shaft, and the driving shaft 12, the axes of these two shafts being in substantial alignment. The armature shaft 11

and the driving shaft 12 have at their ends two face plates respectively 13 and 14, and the face plate 13 carries a pin 15 which extends through a slot 16 in the face plate 14, said slot being concentric with the axis of 60 the driving shaft. The face plate 14 carries a pin 17 which is connected to the other pin 15 by means of a spring or other resilient means 18. Upon the edge of the face plate 13 is formed a cam 19, which normally engages a roller 20 which is pinned at 65 21 to a lever 22. This lever is fulcrumed at 23 and the roller is held against the cam by means of spring 24. In Fig. 3 I have shown a modification in which a latch means is 70 added.

In the operation of starting, the latch 25 is released as shown in Fig. 3 in those models in which a latch is used, and the roller allowed to contact with the cam. As the driving shaft is now turned, the pin 17 revolving with the face plate 14 pulls the pin 15 and hence this plate 13 and driven shaft 11 around with it. When the cam 19, however, strikes the roller 20 the cam and the driven shaft will be temporarily stopped owing to the stiffness of the spring 24; the pin 15 therefore being at a standstill while the pin 17 revolves, will cause the spring 18 to be stretched until a tension is reached therein 80 that will be able to overcome the pressure of the spring 24, at which time the cam will be suddenly released and the armature shaft 11 will be caused to rotate for a fraction of a revolution at high speed. If the spring 18 fails for any reason to move the cam 19 over the roller 20 the end of the slot 16 will strike the pin 15 and positively release the cam. At 90 the instant of release the roller 20 acting on the rear face of the cam will greatly accelerate the motion of the cam. This snap action is so timed as to correspond with the point of ignition of the engine with which it is connected. As a result the spark produced by the magneto is as powerful as that 100 which would be produced if the engine were running at a very high rate of speed.

After the engine is in operation and has attained a considerable speed, the roller 20 may be held out of contact with the cam by means of the lever 22, or a means, such as that shown in Fig. 3 may be employed for holding the roller out of contact with the cam.

While I have shown but two modifications 110

of my invention, it is to be understood that others are possible. I desire therefore that it shall be understood that other changes in the construction and arrangement of parts 5 may be made without departing from the spirit and scope of the invention as covered by the appended claims:

1. In a driving means, a driving shaft and a driven shaft, yieldable means connecting 10 the two shafts, a projection carried by the driven shaft and a spring pressed roller adapted to engage the projection.
2. In a driving means, a driving shaft and a driven shaft, yieldable means connecting 15 the two shafts, a projection carried by the driven shaft, a spring pressed roller adapted to engage the projection, and means for holding the roller out of engagement.
3. In a driving means, a driving shaft and a driven shaft, yieldable means connecting 20 the two shafts, and a spring pressed roller adapted to engage a projection on the driven shaft first to retard and then to accelerate the driven shaft.
- 25 4. In an impulse starter, a driving shaft

and a driven shaft, a cam on the driven shaft, and means for engaging the cam to retard its motion and to accelerate its motion after release.

5. In a driving mechanism, a driving 30 member and a driven member substantially in alignment, a yieldable driving connection between the members, a cam on the driven member having front and rear faces, and means in the path of the cam adapted to 35 engage the front face to retard the driven member and to engage the rear face to accelerate the driven member.

6. In a driving mechanism, a driving 40 member and a driven member yieldably connected together, a cam on the driven member having two inclined faces, means adapted to engage one face of the cam to retard the driven member and to engage the other face to accelerate the driven member, and means 45 for moving the first named means out of the path of the cam.

In testimony whereof I affix my signature.

F. D. HOWE.
